ATTORNEY.

UNITED STATES PATENT OFFICE.

ELWOOD RIGGS, OF OMAHA, NEBRASKA.

DESIGN FOR A NOSE-GUARD.

42,976.

Specification for Design.

Patented Sept. 3, 1912.

Application filed January 31, 1912. Serial No. 674,619. Terms of patent 14 years.

To all whom it may concern:

Be it known that I, ELWOOD RIGGS, a citizen of the United States, residing at Omaha, in the county of Douglas and State of Nebraska, have invented a certain new, original, and ornamental Design for a Nose-Guard, of which the following is a specification.

In the accompanying drawing which forms a part of this specification the figure is an elevation of a nose guard embodying my design.

I claim:

The ornamental design for a nose guard, as shown.

ELWOOD RIGGS.

Witnesses:

G. M. MATTSON,
ROY J. DUNN.
